UNITED STATES PATENT OFFICE.

FRANK JOHNSON, OF NEW YORK, N. Y., ASSIGNOR TO ELEVATOR SUPPLIES COMPANY, INC., A CORPORATION OF NEW JERSEY.

DUMB-WAITER CAR.

1,301,569.

Specification of Letters Patent. Patented Apr. 22, 1919.

Application filed August 4, 1917. Serial No. 184,375.

To all whom it may concern:

Be it known that I, FRANK JOHNSON, a citizen of the United States, residing at New York city, N. Y., have invented certain new and useful Improvements in Dumb-Waiter Cars, of which the following is a clear, full, and exact description.

This invention relates to improvements in dumb-waiter cars or the like. When an automatic dumb-waiter is used for carrying trucks, a great difficulty is frequently experienced in getting the car to stop exactly level with the floor, this being partly due to the stretching of the hoisting cables and partly to the varying load in the car at different times. Some of the objects of the present invention are to provide a threshold or bridge which will take up the inequality between the car and the platform or floor at which the car is to stop, will be out of the way while the car is in motion and at the same time will provide a guard in the car to keep the truck from rolling out of the car while the car is in motion. Another object of the invention is to provide a bridge for use in connection with a moving car and a platform, which bridge will have its operation controlled by the mechanism used for the starting and stopping of the car. Other objects of the invention are to provide practical and efficient means for the purpose intended.

These being among the objects of the present invention, the same consists of certain features of construction and combinations of parts to be hereinafter described and then claimed with reference to the accompanying drawings illustrating a suitable embodiment of the invention and in which—

Figure 1 is a vertical section of a dumb-waiter shaft and a car therein equipped with the present improvements;

Fig. 2 is an enlarged vertical section on the line 2—2, Fig. 3, of a car provided with the present improvements;

Fig. 3 is a horizontal section on the line 3—3, Fig. 2; and

Fig. 4 is an enlarged detail section on the line 4—4, Fig. 3.

Referring to the drawings, the dumb-waiter shaft 10 connects two floors or platforms 11, 12, while a dumb-waiter 13 is adapted to move in said shaft, it being provided with any suitable hoisting mechanism such as 14, operated by a motor 15. Any

suitable electrical devices may be used to operate the motor 15, and in the drawings there are shown a dynamo 16 connected by wires 17 and 18 to a circuit closing device 18^a in the car. Of course, it is to be understood that any suitable electrical devices may be used such as are used in connection with automatic dumb-waiters, but the drawing illustrates a simple form of the mechanism which may be used to start and stop the car or dumb-waiter. The wire 17 is connected with the motor 15 of the hoisting mechanism.

A threshold or bridge 20 is carried by the car 13 at the floor or bottom 19 thereof, said bridge being located between opposite sides of the car and being provided with pivots 21 at its opposite ends which turn in suitable bearing brackets 22 secured to said opposite sides of the car. Attached to one of the pivots 21, is a crank 23 which is pivotally connected to a connecting rod or link 24 which extends upwardly to the top of the car and is pivotally connected with a lever 25 which is pivoted at 26 on a support 27 attached to the top of said car. It will be seen that by operating the link 24 the pivoted bridge 20 will in turn be operated and such operation is preferably accomplished by the following means. A solenoid 28 is suitably mounted on top of the car 13 in upright position and its armature 29 is pivotally attached to the lever 25. The wire 17 passes through the solenoid 28 so that the motor 15 and the solenoid are in the same circuit. The said solenoid acts upon the link devices referred to so as to raise the threshold or bridge 20 to the position shown in dotted lines in Fig. 4. In this position the bridge 20 will constitute a guard standing upwardly from the floor 19 of the car so as to prevent a truck on the car from rolling off. When the car reaches a floor or platform, the solenoid 28 no longer acts and a spring 30, which was put under tension by the previous energization of said solenoid, is allowed to expand and act to throw the bridge 20 outwardly from the car into about the position shown in Fig. 1. Said spring is coiled around a rod 31 which is pivoted at its upper end to the lever 25 and is guided in a guide bracket 32 attached to the car, said spring resting upon said bracket at one end and at the other end suitably connected with the upper end of said

rod 31. It will be noticed from Fig. 4 that the pivots 21 are at one side of the tread surface of the bridge so that when the bridge is in horizontal position its tread surface 5 will be substantially flush with the floor surface of the car.

The operation is preferably as follows. Assuming that a truck has been placed on the car and it is desired to carry it from the 10 floor 11 up to the floor 12. The switch 18^a is closed thereby closing the motor circuit and operating the motor 15, thus starting the car upwardly. At the same time, the solenoid 28 is energized thereby acting through the 15 link mechanism described so as to move the bridge 20 into the car and place it in upright position, thereby clearing the dumb-waiter shaft 10. When the car reaches the floor 12, the operator opens the circuit there- 20 by stopping the motor and de-energizing the solenoid 28, which allows the tension of the spring or power device 30 to act upon the link mechanism and move the bridge 20 outwardly from the car and against the floor 25 12. When the movement of the car is reversed, the bridge 20 will be automatically raised out of the way of the shaft 10.

It is obvious that the present invention is not limited to use in connection with 30 dumb-waiters as it is capable of more extended use as for instance in connection with a railway car. The invention is obviously susceptible of a wide range of modification, without departing from the spirit 35 and scope thereof as expressed in the claims.

What I claim as new is:

1. In apparatus such as described, the combination of a car, means for operating said car, a platform, a movable bridge to 40 provide a passageway between the two, and means independent of said platform for operating said bridge, comprising a combined pull and push rod connected with said bridge, said bridge operating means being 45 controlled from the means for operating said car, to move said bridge into and out of using position relatively to said car and platform.

2. In apparatus such as described, the 50 combination of an elevator car, means for operating said car, the floors of a building, a movable bridge to provide a passageway between said elevator car and any one of said floors, means independent of said floors for 55 operating said bridge, comprising a combined pull and push rod connected with said bridge, said bridge operating means being controlled from the means for operating said car, to move said bridge into and out of 60 using position relatively to said car and any one of said floors.

3. In apparatus such as described, the 65 combination of a car, mechanism for stopping, starting and moving said car, a plat- form, a movable bridge, and means inde-

pendent of said platform and controlled by the mechanism for stopping, starting and moving said car, for operating said bridge, to move it automatically to connect said car and platform as the car comes to a stop 70 thereat and to move it to disconnect said car and platform as said car begins to move therefrom.

4. In apparatus such as described, the combination of a car, mechanism for stop- 75 ping, starting and moving said car, a plat- form, a movable bridge pivotally mounted on said car and means on said car for op- erating said bridge, and depending upon the mechanism for stopping, starting and 80 moving said car for its operation, to move said bridge automatically to connect said car and platform as the car comes to a stop thereat and to move it to disconnect said car and platform as said car begins to move 85 therefrom.

5. In apparatus such as described, the combination of a car, mechanism for mov- 90 ing said car, a platform, a movable bridge mounted on said car, link mechanism 95 mounted on said car and connected with said bridge, and devices controlled by the mechanism for moving said car and arranged thereon for operating said link mechanism from within said car to move said bridge be- 95 tween said car and platform.

6. In apparatus such as described, the combination of a car, a platform, a pivoted bridge, operating means for said bridge comprising a portion movable with said bridge 100 and a combined pull and push rod connected at one end with said portion to move said bridge to connect or disconnect said car and platform, a magnetic device for acting at the other end of said rod on said operating 105 means, when energized, to move said bridge in one direction, and a power device for act- ing on said operating means, when said magnetic device is de-energized, to move said bridge in the opposite direction. 110

7. In apparatus such as described, the combination of a car, a platform, a pivoted bridge adapted to swing upwardly toward and outwardly from said car and having a rigid extension beyond its pivot, operating 115 means connected with the said rigid exten- sion of said bridge to move it to connect or disconnect said car and platform, a magnetic device, means for energizing the latter for causing it to act on said operating means to move said bridge to upstanding position and maintain it in that position until said car is opposite said platform, and a power de- 120 vice for acting on said operating means, when said magnetic device is de-energized by 125 the said energizing means, to move said bridge to lowered connecting position when the bridge is opposite said platform.

8. In an elevator, the combination of an 130 elevator car, a bridge pivotally mounted on

said car and adapted to be swung upwardly toward and outwardly away from said car and having a rigid extension beyond its pivot, means connected with the said rigid 5 extension and adapted to move said bridge to connect it with a floor of a building, and an electro-magnetic device for positively acting on said bridge-moving means to swing said bridge into upstanding position 10 relatively to said floor, and to hold it in that position as long as desired.

9. In an elevator, the combination of an elevator car, a bridge movably mounted on said car, automatic means carried by said 15 car and free to move said bridge to connect it with a floor of a building, means for actuating said bridge-moving means to move said bridge away from said floor, electrically operated means for stopping and starting 20 said car, and an electrical device controlled by said electrically operated means, for controlling both of said bridge actuating means.

10. In an elevator, the combination of an elevator car, a bridge movably mounted at 25 the bottom of said car, and adapted to be moved to upstanding position above the floor of said car to provide a guard, magnetic means for moving said bridge to that position and to magnetically hold it fixed in 30 that position, and means associated with said bridge-moving means for moving said bridge outwardly from said car and to a floor of a building when said magnetic hold is released, said two means comprising a lever 35 mounted on said car, and a magnet and spring acting on said lever in opposite directions, said lever having a connection with said bridge.

11. In an elevator, the combination of an 40 elevator car, a bridge pivotally mounted at the bottom of said car, and adapted to be moved to upstanding position above the floor of said car to provide a guard, electro-magnetic means comprising a lever, pivoted in 45 parallelism with the said bridge, for swinging said bridge to that position and for mag-

netically holding it in that position, and pressure means associated with said bridge moving means and bearing on said lever, said pressure means being placed under tension when said bridge moving means so operates, for swinging said bridge outwardly from said car and to a floor of a building 50 when said tension is relieved and exerted.

12. In an elevator, the combination of an 55 elevator car, a bridge pivotally mounted at the bottom of said car and adapted to be moved to upstanding position above the floor of said car to provide a guard, an electro-magnetic device, linkage comprising pivoted 60 members connecting the movable members of said device with said bridge, for swinging it into said car, means for energizing said magnetic device and causing it to so operate said bridge and to hold said bridge 65 in that position while said magnet is energized, and power means associated with one of the pivoted members of said linkage and adapted to be placed under stress as said device is energized, the tension of said power 70 means being adapted to be exerted on said linkage to swing said bridge away from said car and toward a floor of a building as said magnetic device is deenergized.

13. The combination with an elevator car, 75 of a bridge pivoted at the bottom of said car and having a normal upstanding position above said bottom, whereby it is adapted to constitute a guard, said bridge having a rigid extension beyond its pivot, and means 80 independent of the elevator shaft for the operation of said bridge, and having a connection with the said extension of said bridge for swinging it from said position outwardly 85 from said car bottom.

Signed at Hoboken N. J. this 24th day of July 1917.

FRANK JOHNSON.
